(57) **CLAIM**

The ornamental design for a styled blanket scarf, as shown and described.

DESCRIPTION

FIG. 1 is a rear perspective view of the styled blanket scarf of the present disclosure when the styled blanket scarf is laid out flat;

FIG. 2 is a front perspective view of the styled blanket scarf of FIG. 1 when the styled blanket scarf is laid out flat;
FIG. 3 is a top elevation view of the styled blanket scarf of the present disclosure when the styled blanket scarf is laid out flat;

FIG. 4 is a bottom elevation view of the styled blanket scarf of the present disclosure when the styled blanket scarf is laid out flat;

FIG. 5 is a left side elevation view of the styled blanket scarf of the present disclosure when the styled blanket scarf is laid out flat;

FIG. 6 is a right side elevation view of the styled blanket scarf of the present disclosure when the styled blanket scarf is laid out flat;

FIG. 7 is a rear plan view of the styled blanket scarf of the present disclosure when the styled blanket scarf is laid out flat;

FIG. 8 is a front plan view of the styled blanket scarf of the present disclosure when the styled blanket scarf is laid out flat;

FIG. 9 is a top perspective view of the styled blanket scarf of the present disclosure;

FIG. 10 is a bottom perspective view of the styled blanket scarf of the present disclosure;

FIG. 11 is a front elevation view of the styled blanket scarf of the present disclosure;

FIG. 12 is a rear elevation view of the styled blanket scarf of the present disclosure;

FIG. 13 is a left side view of the styled blanket scarf of the present disclosure;

FIG. 14 is a right side view of the styled blanket scarf of the present disclosure;

FIG. 15 is a right side view of the styled blanket scarf of the present disclosure shown in an environment of use thereof;

FIG. 16 is top elevation view of the styled blanket scarf of the present disclosure;

FIG. 17 is bottom elevation view of the styled blanket scarf of the present disclosure;

FIG. 18 is a front perspective view of the styled blanket scarf of the present disclosure shown in an environment of use thereof; and,

FIG. 19 is a front perspective view of the styled blanket scarf of the present disclosure shown in an environment of use thereof.
